UNITED STATES PATENT OFFICE.

HARRY COOK, OF ST. LOUIS, MISSOURI.

DESIGN FOR A CLOTHES-LINE REEL.

SPECIFICATION forming part of Design No. 23,876, dated December 11, 1894.

Application filed November 12, 1894. Serial No. 528,584. Term of patent 7 years.

To all whom it may concern:

Be it known that I, HARRY COOK, of the city of St. Louis, State of Missouri, have invented a new and original Design for a Clothes-Line Reel, of which the following is a full, clear, and exact description, reference being had to the accompanying drawings, forming a part hereof.

In the drawings: Figure 1 is a side elevation of a clothes-line reel embodying my design. Fig. 2 is a sectional elevation taken on the line $x-x$ of Fig. 1.

The characteristic feature of my design is a rectangular frame 1 having a length in excess of its height, and the upper and lower bars of which are rectangular in cross-section and connected by a series of cylindrical bodies 2 extending parallel with each other, the said frame surmounted by a cylindrical body 3 ex-

tending parallel with said side-bars. A series 20 of short cylindrical bodies 4 are located beneath the lower horizontal bar of said frame with all of their free ends in the same plane.

Mounted on the upper side-bar of the frame 1 and extending parallel therewith is a rectangular body 5, the ends of which are inclined in opposite directions. Short vertical cylindrical bodies 6 connect the horizontal cylindrical body 3 with the body 5.

What I claim is—

The design for a clothes-line reel as herein shown and described.

In testimony whereof I affix my signature in presence of two witnesses.

HARRY COOK.

Witnesses:

C. K. JONES,
JNO. C. HIGDON.
